UNITED STATES PATENT OFFICE

CHARLES T. HOWSON, OF SILVER CREEK, NEW YORK, ASSIGNOR, BY MESNE ASSIGNMENTS, TO HUNTERY MANUFACTURING CO., OF SILVER CREEK, NEW YORK, A CORPORATION OF NEW YORK

GAS-MIXING DEVICE

Application filed November 13, 1924. Serial No. 749,633.

My invention relates to improvements in gas-mixing devices, and more particularly to that type in which a mixing chamber is provided into which air and gas are led to be mixed therein, preparatory to consumption at a burner for heating purposes.

An object of my invention is the provision of a gas-mixing device, which will provide an elongated conduit extending from the point at which the gas or other fuel and air are first brought into contact with each other to the point of consumption, and in which elongated conduit, mixing of the gas and air are carried on to the maximum degree to assure a highly effective mixture with the minimum supply of gas or other fuel; the initial mixture of gas and air taking place in lines of travel at reverse angles with respect to the axis of said elongated conduit.

A mixing device having the objects above-mentioned and others to appear hereinafter, especially when used in connection with a burner for heating purposes, results in a considerable saving of fuel, and due to the thorough mingling of gas and air resulting therefrom, produces a flame which throws off maximum heat units.

With the above and other objects in view, the invention consists in the novel features of construction and in the arrangement and combination of parts to be hereinafter described and more particularly pointed out in the subjoined claims.

In the drawings:—

Fig. 1 is a side elevation of my improved mixing device, part of the conduit leading the mixture issuing therefrom being shown in section.

Fig. 2 is a transverse section taken on line 2—2, Fig. 1.

Fig. 3 is an enlarged longitudinal section of the device.

Fig. 4 is a side elevation of the device embodying my invention in modified form.

The mixing device includes a gas mixer 5, an air inlet tube 6 for said gas mixer having a control valve 7 therein, a gas inlet pipe 8 leading to said mixer and having a control valve 9 therein, and a fan 10 associated with said mixer and in preferred construction re-

ceiving gas and air in commingled form from said gas mixer and forcing the same outwardly through a tube 11 to which a burner or other element (not shown) is connected, said burner or other element being at the point of consumption of the mixture passing through the device.

While my improved device may include any form of gas mixer suitable for the purpose, I herein show a gas mixer such as set forth and claimed in my co-pending application, Serial No. 743,303, filed October 13, 1924, now Patent 1,749,914, issued March 11, 1930, and which comprises a casing or body portion 12 having an air nozzle 13 at one end and having secured to its other end the fan 10.

The casing or body portion comprises an elongated hollow cylindrical member or mixing chamber 14 devoid of physical matter, a hollow head or enlargement 15 co-axial therewith at one end thereof, and an external flange 16 at the other end, which is connected to a second head or enlargement serving as the casing of the fan 10, the interior of said cylindrical member or mixing chamber being aligned with the inlet or eye 17 of said second head or enlargement, or as it may be termed, the fan casing. The first-mentioned enlargement or head of said casing or body portion serves as the inlet end thereof, while the flanged end thereof provides a means of connection to the second head or enlargement which serves as the outlet end.

The hollow head or enlargement 15 is formed by a wall 18 extending outwardly from the inlet end of the elongated cylindrical member or mixing chamber, a cylindrical wall 19, and an outer end wall 20 parallel with and spaced from the wall 18. The wall 20 has an axial threaded opening formed therein into which the air nozzle 13 is threaded.

Into the outer end of said air nozzle, the air inlet pipe 6 is threaded, and it extends into the interior of said nozzle, which is cylindrical a distance inwardly from said pipe, as at 21. From this cylindrical portion the interior of said air nozzle is gradually enlarged toward its inner end by flaring the wall, as at 22. The outer circumferential

surface of said air nozzle is beveled or tapered at its inner end, as at 23, so that a sharp circular edge 24 is provided at the inner extremity of said nozzle.

- 5 At the junction of the outstanding wall 18 with the cylindrical wall of the mixing chamber 14, an internal flange 25 is provided, part of said flange extending into the hollow head or enlargement 15. The inner surface of said 10 flange is tapered inwardly from the hollow head or enlargement to conform to the externally-tapered portion at the inner end of the air nozzle, which inner end said internal flange 25, or at least part thereof, surrounds 15 in spaced relation. The annular inwardly-tapered space 26 thus formed between said air nozzle and said internal flange serves as the gas inlet or passage for the mixing chamber.

By reason of the internal flange 25 extending 20 into the hollow head or enlargement and the air nozzle 18 extending inwardly from the outer wall 20 of said hollow head or enlargement, a substantially annular gas chamber 27 is formed in said hollow head or enlargement, and entering said chamber at one point 25 is the gas inlet pipe 8.

Mounted in the air nozzle is an air deflecting cone 28, the base of which terminates at or near the plane of the inner end of said air nozzle. This cone is spaced from the surrounding wall of the air nozzle to form an annular inwardly-flaring air passage 29. The gas enters the annular gas chamber 27 within said hollow head or enlargement from 35 the gas inlet pipe, the flow of the gas being controlled by the valve 9, and from this annular chamber the gas escapes through the annular inwardly-tapered gas inlet or passage 26 in the form of a circular stream or film. The 40 air passes into the air nozzle from the air inlet pipe 6, the flow of which air is controlled by the valve 7, and it is directed through the annular inwardly-flaring air passage 29 between the inner end portion of the wall of said 45 air nozzle and the air deflecting cone. The circular stream of air thus supplied intersects the inrushing circular stream or film of gas and these two circular streams therefore approach each other and enter the mixing chamber 50 at reverse angles with respect to the axis of said chamber, and under such action an intimate mixing of the two circular streams takes place, not otherwise possible to accomplish. The gas and air thus entering the mixing 55 chamber in intersecting lines and in streams or bodies of circular or annular formation, commingle within the mixing chamber without encountering any obstructing matter or substance and continue through said mixing chamber while disturbed in their 60 respective courses, one by the other only, so that a substantial commingling of gas and air takes place. Said mixing chamber is of even cross-sectional area or transverse dimension 65 throughout its length and as a minimum has

its longitudinal dimension not less than twice its transverse dimension.

Journalized in one of the side walls of the casing 10 of the fan, is a shaft 30, driven by a motor or other suitable power medium, 70 and on this fan is mounted the fan-rotor 31. The casing of the fan has a tangential outlet 32 into which the tube 11 is threaded, and upon rotation of said fan-rotor, the commingled gas and air passing through the 75 mixing chamber 14 are drawn into the fan and are further cut up and caused to commingle in a thorough manner, and the mixture resulting therefrom is driven out of the tangential outlet 32 of the fan casing and 80 passed on to the burner or other element at which the mixture is to be used.

From the foregoing description, it will be apparent that the course through which the gas and air pass from their point of first 85 contact with each other to the point at which the resultant mixture is used, is an extended or elongated one, and during the advancee of the gas and air along this course, they are mixed in a progressively increasing degree.

Experiments showing that a commingling of gas or other fuel, and air passing along an extended course, or maintained in commingled form for a period of time, produces 95 best results and assures a most economical consumption of the fuel; it being, however, understood that a course extended beyond a certain degree would result in the component parts of the mixture separating, and if used under such conditions would be less effective.

In the modification shown in Fig. 4, the fan 10 has its tangential outlet 32 connected to the air inlet pipe 6. Air is drawn into the eye 17 of the fan casing and forced through said pipe under pressure so that the gas passing from the hollow head 15 of the mixer and escaping through the annular gas inlet passage 26 is intersected by an annular body of air under accelerated speed passing through the annular inwardly-flaring air passage 29. When, however, the fan is used at the inlet end of the gas mixer, the connection between the mixer and the burner or other element at which the mixture is used, is made directly through the tube 11 without passing through a second fan.

Experiments have further shown that when the device is used as illustrated in the modification referred to, economy in consumption of fuel over the common form of gas mixer is attained, but the amount of saving of fuel is small compared to that saved under the system disclosed in Figs. 1 to 3, in which the fan receives the mixture from the gas mixer causing the component parts thereof to be more thoroughly mixed, and delivers it to the point of consumption.

Where in the specification and claims ref- 130

erence is made to "gas", it is intended to include any substance entering the mixing chamber of the device as gas, or capable of being converted into gas within said device.

Having thus described my invention, what I claim is:—

1. A gas-mixing device having means for bringing together annular streams of air and gas in intersecting lines and an elongated passage having as a minimum a longitudinal dimension not less than twice its transverse dimension and having its transverse dimension equal throughout its length, said passage receiving said streams of air and gas at its entrance end at reverse angles with respect to the longitudinal axis thereof and being devoid of physical matter forming part of the device from the point of original contact of the air and gas with each other to the outlet end of said passage so as to prevent separation of the component parts of said mixture before consumption.
2. A gas-mixing device, comprising an elongated gas-mixing chamber devoid of physical matter forming part of the device and having means connected to one end thereof to cause annular streams of air and gas to be brought in contact with each other in intersecting planes, said air and gas being brought together at the entrance end of said mixing chamber at reverse angles with respect to the axis thereof and said chamber being cylindrical from end to end and having as a minimum a longitudinal dimension at least twice that of the transverse dimension thereof, said chamber having a smooth wall and being devoid of interior obstructions from end to end thereof so as to assure a thorough commingling of the gas and air under the action of the initial commingling thereof without opportunity for expansion or separation of the commingled air and gas.

In testimony whereof I affix my signature.
CHARLES T. HOWSON.
